[57] CLAIM

The ornamental design for a combined picker and fork,
as shown and described.

DESCRIPTION

FIG. 1 is a perspective view of a combined picker and
fork showing my new design;

FIG. 2 is a bottom plan view thereof;

FIG. 3 is a side elevational view thereof with the oppo-
site view being a mirror image thereof; and,

FIG. 4 is a top plan view thereof.

The broken line showing of a handle in FIG. 1 is for
illustrative purposes only and forms no part of the
claimed design.**FIG. 1**

FIG. 2

FIG. 3

FIG. 4
